FAUCET HANDLE

Marcelo G. Laguera, Monterrey, Nuevo Leon, Mexico,
assignor to Fabricas Orion, S.A., Monterrey, Nuevo
Leon, Mexico, a corporation of Mexico

Filed Aug. 12, 1966, Ser. No. 3,441

Term of patent 14 years

(Cl. D91—3)

FIG. 1.

FIG. 2.

FIG. 3.

FIG. 1 is a perspective view of the faucet handle showing my new design.

FIG. 2 is a top plan view thereof.

FIG. 3 is a side elevation thereof.

The broken line representation of a securing screw and a portion of a faucet valve in FIGS. 1 and 2 is for purposes of illustration only.

I claim:

The ornamental design for a faucet handle, substantially as shown and described.
